ELECTRODE SUPPORTING MEANS FOR
ELECTRICAL PRECIPITATORS

Richard A. Marriott, Salt Lake City, Utah, assignor to American Smelting and Refining Company, New York, N. Y., a corporation of New Jersey

Application June 25, 1952, Serial No. 295,457

3 Claims. (Cl. 183—7)

1

This invention relates to electrical precipitators and particularly to electrical precipitators of the weighted wire electrode type, and provides a bifurcated weight element and guide means therefor.

Breakage of the wire in a weighted wire electric precipitator may take place for a number of reasons, including weakening of the wire due to corrosion or burning due to arcing. Heretofore, when such breakage occurred, it was necessary for personnel to enter the precipitator in order to recover the weight. In many instances, this is a particularly nasty job and may involve considerable hazard especially when the precipitator is coated with noxious dusts or acids and the like. In addition, where the bottom of the precipitator is provided with mechanical means for removing the material precipitated from gases, the weight may fall into and damage the moving parts.

The principal object of the invention is to overcome these difficulties. Another object is to provide an electrical precipitator in which the weight attached to a broken wire may be recovered through the top of the precipitator. These and other objects and advantages will become apparent from the following description in which the invention is described more fully.

Broadly, the invention involves an electrical precipitator of the weighted wire electrode type having a bifurcated weight element attached to and supported by a wire electrode and also having a guide element disposed between the legs of the bifurcated weight. The weighted electrode may be either a discharge or a collector electrode although in most commercial precipitators the wire electrode is a discharge electrode.

Preferably, the weighted element is U shaped. In many precipitator designs, a plurality of spaced vertical wire discharge electrodes are aligned therein in a transverse plane or a series of parallel transverse planes. For these and other wire electrode precipitators, a guide element common to each of the weight elements in any particular grouping may be used, such as, for example, those weights in a single plane or groups of planes or groups within a plane. The weight is supported by the wire electrode and holds the wire taut and straight so as to prevent electrical shorting. The weight may also contact the guide element and be partially supported thereby so long as the weight itself still supplies sufficient tension to the wire to keep it taut and straight.

The guide element may fit loosely between the legs of the weight. It serves to prevent or inhibit swinging of the wire electrode and thereby also prevents electrical arcing. In addition, the

2

guide element serves to catch and retain the weight when for any reason the wire is broken. In this connection, the center of gravity of the weight preferably lies toward the bifurcated ends of the weight at a point below the geometric center of the cross-section of the guide element at the point of contact where the weight rests thereon after the wire is broken. In order that the weight may rest with greater stability on the guide element, the center of gravity of the weight may be disposed substantially in the longitudinal axis of the weight. Additionally or alternatively, the guide member may also be provided with means such as grooves which may loosely and slidably engage the legs of the bifurcated weight so that the guide element will catch and retain the weight upon the breaking of the wire. In the event of breakage, the weight which is retained by the guide element may be fished out through the top of the precipitator.

The invention is further illustrated in the accompanying drawings. It should be understood, however, that the drawings are presented for purposes of illustration and that the invention in its broadest aspects is not limited thereto.

In the accompanying drawings in which like reference characters refer to like parts,

Fig. 1 is a vertical section of a weighted wire electrode precipitator provided with bifurcated weights and guide elements for the weights.

Fig. 2 is a view taken along line 2—2 of Fig. 1.

Fig. 3 is an enlarged view of the wire electrode of Fig. 1 showing the guide element and the bifurcated weight.

Fig. 4 is a view taken along the line 4—4 of Fig. 3.

Fig. 5 is a view similar to Fig. 3 but in which the U shaped weight has a semi-circular shank.

Referring to the drawings, there is shown an electrical precipitator having a casing 10 provided with a removable top 11 and also provided with gas inlet conduit 12 and gas outlet conduit 13. The casing 10 defines a precipitator chamber 14. Disposed in this chamber are a plurality of collector electrodes 15 and weighted wire discharge electrodes 16.

The vertical plate collector electrodes 15 are suitably attached or suspended at spaced intervals in the precipitator in parallel planes therein as shown and may rest on or be slidably attached to channels 18. One of these channels may be grounded through lead 19. The discharge electrodes 16 are also disposed in a series of parallel vertical planes with the electrodes in each plane adjacent a collector electrode. The discharge

electrodes are suspended at spaced intervals from pipes or angle members 20 which may be removably attached to angles 21 and 22. The angles 21 and 22 may be suitably attached to and electrically insulated from the upper portion of the precipitator. One of these latter angles, such as 21, may be connected to a suitable electrical source (not shown) by lead 23.

As shown more particularly in Figs. 3 and 4, the tops of the wire discharge electrodes are attached to angles 20. This may be accomplished by looping the wire through an appropriate hole 24 provided therein and then twisting the wire in the manner shown. A bifurcated weight element 25, preferably U-shaped, is suitably attached at its shank portion to the lower end of the wire electrode and is supported thereby with the legs of the weight substantially vertically disposed. The legs of the weight are spaced from each other so as to fit loosely over a guide element. Preferably, each of these weights is disposed below the lower edge of the collector electrodes 15 and each of the weights in a group of discharge electrodes attached to the same angle 20 are in horizontal alignment. Preferably, also, all the weights in the precipitator are disposed in the same horizontal plane.

The legs of each of the U-shaped weights have disposed therebetween a guide element 26. As shown, a common guide element may be provided for the weights attached to each group of wire discharge electrodes adjacent a collector electrode. The guide elements are preferably rods of circular cross-sectional area although other shapes may also be used. Each of such common guide elements 26 may be removably attached at their ends to angles 27 and 28 respectively. These latter angles may be suitably attached to and supported by angles 21 and 22 respectively by means of the four vertical angles 29. Alternatively, the elements 26 may be attached to the side of the precipitator and may be suitably electrically insulated therefrom.

The guide elements prevent the weights and the wire electrodes from swinging so as to prevent electrical shorting in the precipitator. These guide elements also catch and retain the weights in the event a wire electrode breaks. The weights may contact the guide elements and may be partially supported thereby so long as the wire electrodes bear a sufficient portion of the weight of the bifurcated element to keep the wire taut. Preferably, however, under normal conditions the weights are suspended in the manner shown and out of contact with the guide elements except as the legs of the weights may make contact therewith due to swinging or vibration.

In the preferred embodiment, the center of gravity of each of the U-shaped weights lies in its vertical axis and at a point substantially below the center 30 of the guide element 26. When for any reason a wire electrode breaks, the weight falls and rests stably and loosely upon the guide element, as shown by the dotted line portions of Figs. 3 and 5. From this position, the weight can be fished out of the precipitator through its removable top 11 at any appropriate time such as during a shutdown period. Any suitable device such as a wire provided with a hook or a noose may be used to fish out the weight.

To facilitate the "fishing-out" operation, as well as to assist in guiding the weight over the guide element 26 when installing a new weight through the top of the precipitator, the legs 31

of the weights 25 may terminate in points. Such points may be formed by the edges 32 which may slope upwardly and inwardly. Additionally, the shank portion of the bifurcated weight may be provided with an eye element. In this latter connection, the configuration of the shank of the weight at the bifurcation may be such with respect to the guide element so as to provide an opening between the bifurcation and the guide element when the weight rests on the guide after a wire electrode breaks. Such construction is illustrated in Fig. 3 by the sides 33 and 34 which form a V in the shank portion 35 of the weight 25 and provide the opening 36 when the weight rests on the guide as shown in the dotted-line portion of this figure. Alternatively, as shown in Fig. 5 the weight 25 may be provided with a semi-circular shank 37 which rests loosely on the guide 26 when the wire electrode 16 breaks. Thus, in fishing out the weight a hook may be inserted in the opening 36 of Fig. 3 or a hook or noose may be slipped around and up one of the legs of the weight in Figs. 3 and 5 to engage the weight at its shank portion.

If desired, cross-guide members 39 may also be provided on each side of the weights 25 to prevent or inhibit swinging or vibration of the weights longitudinally of the guides 26. The cross-guide members may be rods disposed transversely of the guides 26 and resting thereon with their ends attached to or resting upon the supports 40. Alternatively, the cross-guide may be small cross-bars of a length sufficient to engage the legs of the weight 25. In such a modification the guide elements 39 may be welded or otherwise suitably attached at right angles to the guides 26 and on each side of the weights 25.

In operation, gases containing suspended matter pass into the electrical precipitator through inlet 12 and then pass upwardly between the electrodes. The particles in the gas, as the gas moves between the discharge and collector electrodes, are moved toward and deposited upon the collector electrodes. The cleaned gas passes out of the precipitator through outlet 13. The deposited material ultimately drops into the bottom of the precipitator which may be of hopper-like construction 38 and also may be provided with mechanical removal means such as a screw conveyor 39. In the event a wire electrode breaks, the weight is retained by the guide element and does not fall into the bottom of the precipitator where it may damage the mechanical removal means.

Alternative to the above embodiment of the drawings, either or both the discharge or the collector electrode may be a weighted wire electrode. Instead of being plate-like structures, the collector electrodes 15 may be tubular in shape having circular or polygonal cross-section areas with each such electrode surrounding one or more discharge electrodes. The gases to be cleaned may also pass vertically downward through the precipitator. The precipitator itself and the elements disclosed therein may be fabricated of any suitable material which will withstand the conditions obtaining therein. Thus, for example, where ordinary dusts are to be treated, the precipitator in its various parts may be fabricated of ordinary steel or special steel, as stainless steel. On the other hand, where acid mists and the like are to be treated, lead coated equipment may be used. The bifurcated weights may be composed of any suitable material which preferably is a dense material such as lead.

The present invention may be embodied in other specific forms without departing from the spirit or essential attributes thereof. The herein-described embodiments, therefore, are to be considered in all respects as illustrative and not restrictive.

What is claimed is:

1. In an electrical precipitator of the weighted wire electrode type, the improvement comprising a bifurcated weight element attached to and supported by a wire electrode, and a guide element disposed between the legs of the bifurcated element said weight element by its mass alone holding said electrode taut, the distribution of the mass of said weight element being such that when unsupported by said electrode said weight rests stably upon said guide with the opening between the legs of the weight disposed below said guide and substantially in vertical alignment therewith.

2. In an electrical precipitator for separating suspended materials from gases, a vertical wire electrode, a U-shaped weight element supported by and attached to the lower end of the wire electrode, and a guide element disposed between the legs of the weight said weight element by its mass alone holding said electrode taut, the distribution of the mass of said weight element being such that when unsupported by said electrode

said weight rests stably upon said guide with the opening between the legs of the weight disposed below said guide and substantially in vertical alignment therewith.

- 5 3. In an electrical precipitator for separating suspended material from gases, a plurality of spaced vertical wire discharge electrodes aligned in a transverse plane in the precipitator and adjacent a collector electrode therein, a U-shaped weight element attached to the lower end of each wire and supported thereby, and a guide element common to each of the weight elements in said plane disposed between the legs of each of said U-shaped elements each of the said weight elements by its mass alone holding its respective wire discharge electrode taut, the distribution of the mass of each of said weight elements being such that when unsupported by its respective wire discharge element each weight rests stably upon said guide with the opening between the legs of the weight element disposed below said guide and substantially in a vertical alignment therewith.
